UNITED STATES PATENT OFFICE.

ADAM McDOWALL MATHESON, OF NEW YORK, N. Y.

VALVE.

1,230,499.

Specification of Letters Patent. Patented June 19, 1917.

Application filed March 13, 1917. Serial No. 154,519.

To all whom it may concern:

Be it known that I, ADAM McDOWALL MATHESON, a citizen of the United States, and resident of New York city, have invented certain new and useful Improvements in Valves, of which the following is a specification.

My present invention relates to improvements in valves designed more especially for controlling the discharge of fluids of such a nature as to render confinement difficult, and the invention aims to provide a simple, economical and efficient form of valve embodying two valve members, both operated by a single controlling means, and in which one will be held closed by the fluid pressure while the other is being opened, whereafter the first valve will be forced open against such fluid pressure.

With the foregoing and other objects in view, the invention includes the novel features of construction and arrangement and combination of parts hereinafter described and particularly described in the appended claim.

An embodiment of my invention is illustrated in the accompanying drawing, in which—

Figure 1 is a sectional elevation of a valve constructed in accordance with my said invention, and

Figs. 2 and 3 are sections on lines 2—2 and 3—3 respectively of Fig. 1.

Referring by reference characters to this drawing, the numeral 1 designates the valve casing provided with means at one end for connecting it to the fluid container, which means may conveniently consist of screw threads indicated at 1^a.

The valve casing has an interior longitudinal passage (preferably cylindrical) which is divided into two valve chambers 1^b and 1^c by an internal flange 1^d having a central opening and providing oppositely facing valve seats.

A pair of opposed valves 2 and 3 are located respectively in the chambers 1^b and 1^c and are movably guided therein and have end portions suitably shaped to coöperate with the oppositely faced valve seats, as by forming them of cone shape, as indicated at 2^b and 2^c.

The bodies of these valves are arranged to permit fluid to pass them when unseated, which may conveniently be accomplished by making their cylindrical portions of less di-

ameter than the valve chambers. The movement of the valve member 3 within its chamber 1^c may be limited by a plug 4 screwed into the end of the casing and provided with a fluid pressure 4^a.

One of the valve members, as for example, member 2, has a threaded axial extension 2^a which engages a corresponding threaded axial recess in the opposing member. The valve member 3, while capable of longitudinal movement, is held against rotation by suitable means, such for example as a longitudinal pin *c* mounted in the plug 4 near the edge thereof, which pin engages a corresponding groove in the wall of the valve member.

The other valve member 2 is capable of rotary as well as longitudinal movement, and it will be seen that if said member 2 is rotated in one direction, the threaded extension will be unscrewed from the recess in the valve 3, while rotation in the other direction will screw said extension into the recess. As the valve 3 seats in the direction of flow of fluid through the casing, it will be held against the coacting valve seat during such unscrewing action as long as valve member 2 is capable of longitudinal movement away from its valve seat, but as soon as such longitudinal movement is checked further rotation will force the valve 3 away from its seat against the fluid pressure.

A convenient means for effecting and limiting this movement of the valve member 2 is to provide a rotatable member 5 journaled in a suitable screw plug or stuffing box in the end of the casing and capable of being rotated by a hand wheel 6.

This member 5 has a transverse slot 5^x and a corresponding slot 2^x is formed in the end of the valve member 2. A key piece 7 is secured in one of said slots, for example slot 2^x, and projects into the other slot so as to cause said members 2 and 5 to rotate together while permitting relative longitudinal movement.

Supposing both valves to be seated, rotation of the hand wheel 6 in a counter-clockwise direction will unscrew the threaded extension of the valve member 2, and as the valve 3 is held seated by the fluid pressure the valve member 2 will recede from its valve seat until its rear end contacts with the front end of the rotatable member 5, which, being incapable of longitudinal movement, will arrest further backward

movement of the valve body 2. Continued rotary movement of the hand wheel will cause the unscrewing action of the threaded extension of the member 2 to force the valve member 3 away from its seat against the fluid pressure as said valve member 3 is held against rotary movement in the valve casing by the tongue and groove engagement hereinbefore described.

10 Rotation of the hand wheel in a clockwise direction will produce a screwing action on the threaded extension with the result that the valve member 3 will first be seated under the fluid pressure and thereafter the valve member 2 will be seated, and both valves pressed tightly against their seats by the tightening of the threaded extension.

15 The outlet from the valve chamber is in the shape of a passage 8 which may be placed in communication with any suitable means for receiving the fluid, a convenient form of connection to such receiver being in the shape of the screw threads 9. A safety outlet is also provided is the shape of a passage 10, the outlet of which is closed by a screw

20 plug 11 having a fusible material 12 filling a passage therethrough as shown, or the outlet may be closed by a metal diaphragm or other suitable device.

Having thus described my invention, what I claim is:—

25 In a valve of the character described, a valve casing having alined valve chambers with an intervening double faced valve seat, one of said chambers constituting an inlet passage, a floating valve located in said inlet passage and having means for holding the same against rotary movement, a screw plug in the end of said inlet chamber for limiting the movement of said floating valve, said 30 plug having a fluid passage, a valve in the other chamber mounted to have rotary and longitudinal movement therein, one of said valves having an axial threaded extension engaging the corresponding recess in the 35 other valve, and means for rotating said second valve and limiting the longitudinal movement thereof, substantially as described.

40 In testimony whereof, I affix my signature.
45 ADAM McDOWALL MATHESON.
